PEN

Ernst A. Wiegman, New York, N. Y.

Application November 28, 1938, Serial No. 242,668

6 Claims. (Cl. 120—110)

The present invention relates to a novel type of pen useful for drawing lines, making dots, lettering and the like.

One object of my invention is to provide pens with which lines of relatively great thickness and length can be drawn with ink, water colors or the like in an accurate manner and without the danger of blotting, smearing, obtaining ragged edges or similar imperfections.

Another object of this invention is to provide pens with which it is possible to make dots of round, oval, rectangular and various other shapes in a positive manner by simple application of said pens to a suitable surface without necessitating movement of the pens over said surface.

Further objects of my invention will be seen in the description following hereinafter.

I have found that a pen which has as an essential feature one or more capillary passages for the passage of a liquid from a so-called tank to the contact area, the sum total area or areas of said capillary passage or passages, respectively, being relatively small in comparison to the areas of either the tank or the contact area, is capable of accomplishing the objects above set forth and hereinafter appearing, in an excellent manner.

In order to more fully illustrate my invention, reference is made to the accompanying drawing 30 wherein:

Figure 1 is a front view of one modification of a pen in accordance with my invention,

Figure 2 is a side-sectional view of the same pen taken through section line A—A' of Figure 1,

Figure 3 is a cross-sectional view of the capillary passages of the pen illustrated in Figure 1 taken through section line B—B',

Figure 4 is a front view of another modification of a pen in accordance with my invention,

Figure 5 is a side-sectional view of the pen illustrated in Figure 4 taken through section line C—C', and

Figure 6 is a rear view of the pen shown in Figure 4,

Figure 7 is a rear view of still another modification.

Examination of Figures 1 to 3 inclusive will show that a pen of this modification comprises a curved portion 1 which fits into the end of an ordinary pen holder, tank or reservoir 2, a hole 3 by means of which two capillary passages 4 are formed and a contact line 5. In operation, a liquid such as ink, for example, is introduced into reservoir 2. By capillary action, a portion of the ink flows to the contact area by way of the

capillary passages 4. By reason of the relatively small total area of the two capillary passages, the quantity of ink at or near the contact area before, during and after application of the pen to a surface such as paper is positively controlled so as to eliminate the possibility of making blots and the like by an over-supply of ink at or near said area. At the same time, however, the passages allow a sufficient quantity of ink to flow to the contact area to insure an even and full line when a filled pen is drawn over the surface of a sheet of paper.

Referring now to Figures 4 to 6 inclusive, it may be seen the pen therein illustrated represents a different modification although its operation is based on the same principle. Its primary difference is that it has a circular contact area 6 to which ink or the like flows through capillary passages 4 formed by elongated hole or aperture 3. In operation, the control exerted on the flow of ink by the capillary passages 4 is such that a uniformly thin film of ink is continually maintained at and within circular contact area 6. With this pen it is possible to make a perfectly round dot without incurring the risk of making a blot, and it is also possible to draw straight or curved lines or to use it for lettering.

Another modification suitable for making rectangular dots is illustrated in Figure 7. Rectangular contact area 7 operates on the same principle as the circular contact area 6 of the pen shown in Figure 6. In the hands of a skilled lettering artist, very pleasant effects can easily be obtained by means of this rectangular pen point.

It is to be understood that many modifications of the pens illustrated in the accompanying drawing are possible and are within the contemplation of the instant disclosure. Thus, for example, it is possible to have but one capillary passage so that the lower portion of the pen will have the appearance of an inverted T. It is also possible to vary the size and shape of the hole illustrated in the drawing by means of which two or more capillary passages are formed. The shape of the contact surface may be square, oval, rectangular, hexagonal, etc., as well as circular or linear as shown in Figures 4 and 1 respectively. The bottom portion of the pen comprising the capillary passage or passages may be centered with respect to the reservoir as shown in the drawing or be positioned to one side. Furthermore it is possible to provide a single reservoir with a number of such "bottom portions" so as to facilitate the drawing of parallel lines.

The pens herein described are especially useful for the drawing of relatively thick lines and by reason of the control over the flow of ink exercised by the capillary passages, overcome the disadvantages of the pens hitherto placed on the market to serve that purpose.

The method of manufacturing these pens is comparatively simple. In most cases a pen may be made by placing a suitable piece of metal into die press, shaping it and folding the shaped piece so that a capillary passage or passages and contact surface or surfaces are thereby formed. It is of course also possible to make these pens of synthetic materials such as resins, polymerization products and the like. When a pen such as that illustrated in Figure 4 is made, the circular contact surface is in fact formed by two half rings which are brought together by the folding operation.

It is to be understood that the scope of my invention is not to be limited to the modifications specifically set forth in the present specification but includes all modifications which are based on the same principle and otherwise come within the spirit of this disclosure.

I claim:

1. A pen comprising a reservoir, a ring-shaped contact area and capillary passages leading from said reservoir to said contact area, the total

area of said passages being less than that of the ring-shaped contact area.

2. A pen comprising a reservoir, a ring-shaped contact area and two capillary passages leading from said reservoir to said contact area, the total area of said two passages being less than that of the ring-shaped contact area.

3. A one-piece metal pen comprising a reservoir, a ring-shaped contact area and two capillary passages leading from said reservoir to said contact area, the total area of said two passages being less than that of the ring-shaped contact area.

4. A pen comprising a reservoir, a circular, ring-shaped contact area and two separated capillary passages leading from said reservoir to said circular contact area, the total area of said two passages being less than that of the circular contact area.

5. A pen comprising a reservoir, a rectangular, ring-shaped contact area and two separated capillary passages leading from said reservoir to said rectangular contact area, the total area of said two passages being less than that of the rectangular contact area.

6. A pen comprising a reservoir, a linear contact area and two capillary passages leading from said reservoir to said linear contact area, the total area of said two passages being less than that of the linear contact area.

ERNST A. WIEGMAN. 30
